PROCESS FOR TREATING HYDROCARBONS

Malcolm P. Youker, Bartlesville, Okla., assignor to
 Phillips Petroleum Company, Bartlesville,
 Okla., a corporation of Delaware

Application July 23, 1935, Serial No. 32,805
 Renewed April 21, 1938

11 Claims. (Cl. 196—10)

This invention relates to a process of treating hydrocarbons and relates particularly to a process for converting normally gaseous hydrocarbons to normally liquid hydrocarbons.

5 An object of the present invention is to provide a process for treating a mixture of normally gaseous hydrocarbons under a condition best suited to effect conversion of the individual hydrocarbons in the mixture to a maximum yield 10 of normally liquid hydrocarbons.

More specifically an object of the present invention is to segregate lighter from heavier normally gaseous hydrocarbons contained in a starting mixture of such materials and to treat these 15 groups both separately and in combination to obtain an increased yield of liquid products therefrom.

In one form my new invention comprises the following steps, separation and removal of normally gaseous hydrocarbons such as ethane, propane and butane from gas mixtures also containing fixed gases such as methane, hydrogen etc.; division of the separated gases into a lighter portion consisting principally of ethane and propane and a heavier portion consisting largely of butane; subjection of the lighter portion to high temperature conditions suitable for converting the saturated hydrocarbons contained therein to the corresponding unsaturated hydrocarbons; 20 mixing the resulting unsaturated hydrocarbons with the heavier portion of the gases previously separated from the original charge and converting the resulting mixture under conditions of temperature and pressure particularly suited to effect polymerization of this mixture to normally liquid hydrocarbons predominantly of the motor fuel range.

Other advantages of my new invention reside in the specific method of effecting, in an economic and efficient manner, the separation of the normally gaseous materials into the aforementioned lighter and heavier portions and in the combination of this method with the conversion steps themselves to produce a high yield 45 of normally liquid hydrocarbons in the motor fuel range.

This specific method consists in abstracting the desired normally gaseous materials as well as heavier materials from a stream of gas such as natural gas which may be supplied directly from gas or oil wells, by absorption in a liquid absorbent under relatively high pressure; flashing of the enriched absorbent under somewhat lower pressure to separate therefrom the lighter 50 normally gaseous fraction referred to above while

retaining therein the heavier normally gaseous fraction and normally liquid materials; then flashing the partially denuded absorbent under still lower pressure to vaporize and strip the remaining absorbed material therefrom; then 5 compressing these latter vapors and rectifying them to separate the said vapors into the aforementioned heavier normally gaseous portion and stable normally liquid material suitable for direct inclusion in motor fuel.

10 Some of the normally gaseous constituents recovered from the products of the subsequent conversion steps may be introduced into the above described absorption system to recover recycle material from these constituents without 15 the necessity of adding additional equipment for this purpose.

Other objects and advantages of my new invention will be readily apparent from the following description taken in conjunction with the 20 attached drawings which illustrate one diagrammatic form of apparatus which may be used for successfully practicing the invention.

Referring to the drawings hydrocarbon gas such as natural gas direct from gas or oil wells, 25 cracking or crude still gases or the like, is delivered through a pipe 1 under relatively high pressure into an absorber 2. If the gas supply is not available under a sufficiently high pressure a pump 3 in pipe 1 may be utilized to increase the pressure of the gas. The gas entering absorber 2 flows upward therethrough and is contacted therein with a down flowing stream of absorption oil which may be a product recovered from the process or extraneously introduced 30 liquid suitable for this purpose. The initial quantity of absorption oil is introduced by way of pipe 4 in which is mounted a valve 5 and a pump 6 which pumps the absorption oil into the upper portion of absorber 2. The gas unab- 35 sorbed in absorber 2 passes therefrom through a pipe 7 in which is mounted a valve 8. Valve 8 is manipulated to hold any desired pressure on absorber 2. This pressure is usually sufficiently high to cause absorption of all of the 40 constituents of the entering gas except the major portion of the methane and lighter fixed gases such as hydrogen, nitrogen, carbon dioxide, etc. and some of the ethane. All of the other constituents of the entering gas comprising part of the 45 ethane, substantially all of the propane, butane and the heavier normally liquid materials are absorbed in the absorption oil and pass from absorber 2 through a pipe 9 in which is mounted a valve 10 into a separator 11. In passing from 50

absorber 2 the pressure is reduced on the enriched liquid entering separator 11 and a portion of the absorbed material is flashed from the enriched oil as a result of the reduction in pressure, and passes from the separator 11 through a pipe 12 in which is mounted a valve 13 which is manipulated to maintain such a pressure in separator 11 as to permit only a lighter portion of the normally gaseous materials contained in the enriched absorbent to vaporize in separator 11. This lighter portion of the normally gaseous materials comprising ethane and a portion of the propane and such smaller portions of butane and heavier fractions as may vaporize under the particular superatmospheric pressure and temperature employed, the temperature being generally atmospheric, will then be further processed as will be more fully described hereinafter.

20 The partially denuded absorption oil will be withdrawn from separator 11 through a pipe 14 in which is mounted a valve 14A and again flashed under further reduced pressure in a stripping chamber 15 wherein the remaining absorbed material is stripped from the absorption oil as a result of the reduction in pressure, assisted if necessary by heat applied in the stripper 15, or if desired by suction applied by a combination vacuum pump and compressor 17 mounted in a pipe 16 which leads from the upper portion of stripper 15. The denuded absorption oil which will collect in the lower portion of stripper 15 will be withdrawn therefrom through a pipe 18 in which is mounted a valve 19 into pipe 4 by pump 6 which then recirculates the denuded oil to absorber 2. The stripped vapors removed in stripper 15 pass through pipe 16 and are compressed by compressor 17 and discharged into a stabilizing column 20 wherein 40 these vapors, which contain the heavier portion of the normally gaseous hydrocarbons originally removed from the inlet gas by absorption and normally liquid material, such as pentane and heavier fractions generally termed natural gasoline, are fractionated to sharply separate the heavier normally gaseous materials consisting principally of butane and smaller amounts of propane from the normally liquid materials. Heat supplied by a heating coil 21 located in 50 the lower portion of stabilizer 20 is used if necessary to assist in the separation. Vapors separated in stabilizer 20 pass upward therethrough and those which reach the upper portion thereof pass therefrom through a pipe 22. These vapors 55 which comprise principally butane and some propane pass through a condenser 23 where the major portion of the butane is condensed leaving most of the propane uncondensed. The mixture of liquefied butane and uncondensed propane then passes into a separator 24 wherein the gaseous propane will separate from the liquefied butane and will pass from separator 24 through a pipe 25 and a valve 26 into pipe 12 wherein the propane mixes with the similar light 60 gases passing through pipe 12 as heretofore described and is conducted to further processing steps as will be later described. Valve 26 is manipulated to regulate the pressure in separator 24, condenser 23 and stabilizer 20 in any manner necessary to assist in effecting the desired separation in stabilizer 20. A portion of the liquefied butane which will collect in separator 24 will be returned therefrom through a pipe 27 and a valve 28 by a pump 27A to the upper portion 70 of stabilizer 20 to serve therein as reflux,

sufficient liquid butane being thus returned to cause condensation in stabilizer 20 of all materials heavier than butane contained in the vapors flowing upward in stabilizer 20. The material thus condensed will consist principally of pentane and heavier natural gasoline fractions and will collect in the lower portion of stabilizer 20 whence it will be withdrawn through a pipe 29 by opening a valve 30 in pipe 29. The butane-free natural gasoline thus withdrawn may be 10 utilized in any desired manner though it will usually be blended with the final gasoline product of the system. The remainder of the liquid butane collecting in separator 24 will be withdrawn through a pipe 31 by opening a valve 32 15 and will be further processed in a manner subsequently to be described.

At this point in the process there are available two different materials for further processing. They are a lighter normally gaseous fraction 20 comprising principally ethane and propane, available at this point in vapor form in pipe 12 and a heavier normally gaseous fraction comprising principally butane and some propane, available at this point in liquid form in pipe 31. 25

Taking first the lighter normally gaseous fraction in pipe 12, this material will be compressed by a compressor 33 in pipe 12 and will be pumped thereby through a heating coil 34 mounted in a furnace 35. In passing through the coil 34 the 30 ethane-propane fraction will be heated to a high temperature sufficient to effect conversion of the ethane and propane to the corresponding unsaturated hydrocarbons, namely ethylene and propylene, forming at the same time some fixed gases and materials heavier than propylene. The heated and converted materials will then pass through a pipe 36 in which is mounted a valve 37 into a cooler 38. Valve 37 will be manipulated to hold pressure on the material passing through coil 34. The pressure required will usually be only sufficient to overcome the pressure drop through the succeeding portions of the apparatus but in some cases may be appreciably higher than the minimum pressure required to overcome such 45 friction losses. Since the temperature required to convert ethane and propane to ethylene and propylene is quite high, ranging generally between 1000° F. and 1700° F. depending upon the pressure and the rate of conversion desired, in 50 order to prevent secondary reactions such as excessive polymerization to tars and other heavy carbonaceous materials, rapid cooling of the products leaving coil 34 is usually necessary. To meet this condition cooler 38 may be of special design to effect shock chilling as by direct mixing of cold oil or water with the products leaving coil 34. In any case the products are cooled below an active reaction temperature in 55 cooler 38 from which the partially cooled materials pass through a pipe 39 which leads through a secondary condenser 40 wherein sufficient additional cooling, if necessary, takes place to condense substantially all of the material heavier than gasoline formed in passage through the coil 60 65 34. The resulting heavy condensate together with uncondensed material which consists of the produced gasoline range material, ethylene and propylene, unconverted ethane and propane and fixed gases will pass into a separator 41 wherein 70 the uncondensed material will separate from the relatively heavy normally liquid material. The normally liquid material comprising products generally heavier than gasoline will be removed from separator 41 through a pipe 42 by opening 75

a valve 43 in pipe 42 and will be sent to further fractionating equipment as will be described hereinafter. The uncondensed material containing unsaturated hydrocarbons will be withdrawn from separator 41 through a pipe 44 by a compressor 45 which will compress the unsaturated material to a relatively high superatmospheric pressure and discharge the compressed material into an absorber 46 wherein the compressed gases will be contacted with a stream of absorption oil supplied through a pipe 47 and valve 48 by a pump 49. Such conditions of pressure and volume of absorbent will be maintained in absorber 46 as to cause the absorption oil to absorb substantially all of the ethane-ethylene, propane-propylene and heavier fractions contained in the gaseous material introduced into absorber 46 through pipe 44 and leave unabsorbed only fixed gases such as methane and lighter which will be discharged from absorber 46 through a pipe 50 in which is mounted a valve 51 which will be manipulated to hold any desired pressure on absorber 46. The fixed gases thus discharged may be vented to the fuel system or disposed of in any desired manner. The rich absorption oil containing the absorbed constituents will be withdrawn from absorber 46 through a pipe 52 by opening a valve 53 in pipe 52 and will be discharged into a separator 54 under a pressure somewhat reduced below that maintained in absorber 46. The reduction in pressure effected in separator 54 may be of such degree as to permit flashing from the rich absorption oil of only the lighter fraction of the absorbed constituents, such for example as the ethane-ethylene fraction. These flashed vapors will separate from the partially denuded absorption oil in separator 54 and will be withdrawn therefrom through a pipe 55 in which is mounted a valve 56, by which the desired pressure in separator 54 may be maintained, to a compressor 57 in pipe 55 which will compress the flashed vapors and pump them through a condenser 58 wherein sufficient cooling will be applied to the compressed vapors to liquefy them, if desired, and pump the liquefied material through a pipe 59 and valve 60 into pipe 31 which leads to a further conversion step as will be subsequently described. Instead of discharging the cooled and compressed gas in pipe 59 into pipe 31, valve 60 may be closed and the gases passed through a pipe 61 by opening a valve 62 in pipe 61 into pipe 12 and may thus be recycled through the high temperature conversion coil 34.

55 The partially denuded absorption oil in separator 54, containing the heavier portions of the absorbed gases such for example as the propane-propylene and butane-butylene and gasoline fractions will be withdrawn from separator 54 through a pipe 63 by opening a valve 63A in pipe 63 and will be discharged under still further reduced pressure into a stripper 64 wherein the remaining absorbed material will be stripped from the absorption oil which will then be withdrawn from stripper 64 through a pipe 65 by opening a valve 66 in pipe 65 and returned to pipe 47, through which it will be recirculated to absorber 46 by pump 49 to be re-utilized therein in the manner previously described. The stripping of the remaining absorbed material from the absorption oil in stripper 64 may be effected with the assistance of heat or by suction applied through a pipe 67 by a combination vacuum pump and compressor 68 which will withdraw the stripped vapors from stripper 64, compress them to any desired pressure and introduce them into a stabilizer 69 wherein the compressed vapors will be fractionated to separate gasoline boiling range material from the lighter normally gaseous materials such as the propane-propylene and butane-butylene fractions. The fractionation in stabilizer 69 may be assisted by heat supplied from a heating coil 70 located in the lower portion of stabilizer 69. The stabilized gasoline separated by fractionation in stabilizer 69 will be removed therefrom through a pipe 71 by opening a valve 72 and will be disposed of in any desired manner. Since it is a final product of the process it may be sent to storage or blended with the gasoline previously removed from stabilizer 20 25 20 or with additional gasoline recovered in other steps of the process to be described later.

The normally gaseous fractions separated from gasoline in stabilizer 69 will pass therefrom through a pipe 73 which leads through a condenser 74 into a separator 75. The normally gaseous fractions will be at least partially condensed in condenser 74 and the mixture of condensate and uncondensed vapors will enter separator 75 wherein uncondensed vapors will separate from condensed normally gaseous materials. Some of the condensed liquid in separator 75 will be returned to stabilizer 69 through a pipe 76 and valve 77 by a pump 76A to be utilized as reflux to effect the desired fractionation and separation of gasoline from lighter constituents in stabilizer 69. This reflux material will generally comprise the butane-butylene and propane-propylene fractions of the vapors passing from stabilizer 69. The remainder of this liquefied material collecting in separator 75 and not utilized for reflux as described will be withdrawn from separator 75 through a pipe 78 and valve 79 and passed into pipe 59 and thence into pipe 31 for further processing as will be later described. The uncondensed vapors separated from the condensate in separator 75 will be withdrawn therefrom through a pipe 80 in which is mounted a valve 81 which will be manipulated to maintain any desired pressure on stabilizer 69 and its attendant auxiliary equipment. The vaporous fraction thus withdrawn will consist principally of the remainder of the ethane-ethylene fraction not previously removed in separator 54, and a portion of the propane-propylene fraction and will be passed to pipe 55 to be further handled with the material passing through pipe 55 as previously described.

At this point in the process the following has been accomplished, a gas supply has been scrubbed to remove substantially all the liquefiable materials contained therein and these materials have been separated into normally liquid materials and lighter and heavier normally gaseous fractions, the lighter normally gaseous fraction containing ethane, and propane principally has been subjected to a heating step to convert the major portion of these hydrocarbons to the corresponding unsaturated hydrocarbons which, after separation from fixed gases and normally liquid materials resulting from the conversion reaction, are liquefied and mixed with the originally separated heavier normally gaseous fraction obtained from the initial charge to the process.

This latter mixture is that which is formed in pipe 31 as described above and the description will now proceed from that point. The mixture in pipe 31 which comprises the liquefied heavier portion of the normally gaseous hydrocarbons consisting principally of butane and propane obtained

from the initial charge to the process and collected in separator 24 together with the liquefied normally gaseous products resulting from the conversion of the original lighter normally gaseous fraction in coil 34, is pumped by means of a pump 82 through a coil 83 which is mounted in a furnace 84 thence via a pipe 85 in which is mounted a valve 86 into a separator 87. In passing through the coil 83, the liquefied gaseous materials will be subjected to a temperature ranging generally from 850° F. to 1150° F. and will be maintained under a pressure, regulated by means of valve 86, of above 500 pounds per square inch, usually between 1000 and 3000 pounds per square inch or even higher. Under these conditions the composite liquefied gases passing through coil 83 will be polymerized at least in part to normally liquid materials largely in the gasoline boiling range. Some fixed gases and materials heavier than gasoline will also be formed while some of the charge material may remain unconverted. Upon entering separator 87 the pressure upon the products of the polymerization reaction will be reduced and the products subjected to a fractionation operation to separate the gasoline and heavier materials from the materials lighter than gasoline which consist largely of butane and lighter normally gaseous materials. The gasoline and heavier materials will be withdrawn from separator 87 through a pipe 88 by opening a valve 89 in pipe 88 and will be fed into pipe 42 through which the heavier products obtained from the conversion operation in coil 34 as previously described are being conducted. The resulting mixture in pipe 42 is then conducted to a fractionator 90 wherein this mixture is subjected to a conventional fractionating operation to separate gasoline and any lighter materials which may be contained in the mixture from heavier products of the process. A heating coil 91 in fractionator 90 will supply any heat necessary to effect efficient fractionation. The separated heavier products will be removed from fractionator 90 through a pipe 92 by opening a valve 93 in pipe 92 and will be disposed of in any desired manner.

The lighter than gasoline vapors separated from gasoline and heavier in separator 87 will pass therefrom through a pipe 94 and valve 95 thence through a condenser 96 wherein a portion of the vapors will be condensed and the resulting mixture of condensate and uncondensed vapors will flow from condenser 96 into a separator 97 wherein the condensate which will consist of the heavier portion of the vapors, usually butane and some propane, will separate from uncondensed vapors consisting usually of some propane, ethane and fixed gases. Some of the condensate will be withdrawn from separator 97 through a pipe 98 and valve 99 and will be returned to separator 87 to serve as reflux. Sufficient material will be thus returned to condense substantially all the gasoline and heavier material in separator 87. The remainder of the condensate not utilized as reflux will be withdrawn from separator 97 through pipe 100 by opening valve 101 and will be returned to pipe 31 for recycling through the polymerization coil 83. The uncondensed vapors separated from condensate in separator 97 will be withdrawn therefrom through a pipe 102 and a valve 103 by a compressor 104 which will compress these vapors and discharge them into pipe 1, whereby they are returned to the initial absorption system to effect recovery therein of the lighter gaseous materials such as propane and ethane which may then be

reprocessed along with corresponding constituents recovered from the initial charge to the process as has heretofore been described. Valve 103 in pipe 102 will be manipulated to control the pressure under which the separation in separators 87 and 97 is effected. This will usually be sufficiently high to effect liquefaction of substantially all the butane and a large part of the propane in the vapors leaving separator 87 through pipe 94. Instead of separating the vapors leaving separator 87 into a heavier liquefied fraction and a lighter gaseous fraction all of the vapors may be passed directly from pipe 94 through a pipe 105 and a valve 106 into pipe 102, by closing valve 95. Thus all of these normally gaseous constituents will be mixed with the initial gas charge to the process and reprocessed therewith and the polymerizing operation in coil 83 will become a "once-through" operation instead of a recycling process.

The vapors separated from heavy products in fractionator 90 containing gasoline and some lighter constituents will pass from fractionator 90 through a pipe 107 which leads through a condenser 108 to a separator 109. In condenser 108 gasoline contained in the vapors will be condensed and in separator 109 will separate from uncondensed gases and a portion of the gasoline will be withdrawn from separator 109 through a pipe 110 and a valve 111 and will be returned to fractionator 90 to be utilized as reflux. Sufficient gasoline will be thus returned to effect condensation in fractionator 90 of substantially all materials heavier than gasoline contained in the vapors passing upwards in fractionator 90.

The remainder of the gasoline which will collect in separator 109 will be withdrawn therefrom through a pipe 112 and valve 113 as a final product of the process. This gasoline may be sent to storage separately or it may be blended with the gasolines removed from stabilizers 20 and 69 as previously described. This blended material then becoming the ultimate product of the process.

The vapors lighter than gasoline separated from gasoline in separator 109 will be withdrawn therefrom through a pipe 114 and valve 115 into pipe 102 by means of compressor 104. The vapors will thus be mixed with those from separators 87 and 97 and will thus be returned to the initial steps of the process and subjected to complete reprocessing. Valve 115 will be manipulated to maintain any desired pressure on the fractionating system comprising fractionator 90 and its attendant equipment.

The pressures maintained in the absorption and fractionating system comprising absorber 2, separator 11, stripper 15, stabilizer 20 and the interconnecting pipes, condensers etc. will vary depending on the composition of the charge, the degree of separation desired in vessels 11 and 15 and the degree of fractionation desired in stabilizer 20.

The pressure maintained on the absorption operation in absorber 2 will generally range between 100 and 300 pounds per square inch or higher. The pressure in separator 11 will generally be at least 50 pounds lower than that in absorber 2 depending upon the composition desired in the light gas fraction to be removed from separator 11.

The pressure in stripper 15 will be appreciably lower than that in separator 11 and may even be sub-atmospheric again depending upon what composition is desired in the heavy vapor fraction removed therefrom.

The pressure in stabilizer 20 will be generally

substantially superatmospheric depending upon the degree and type fractionation desired. I have found that pressures above 100 pounds per square inch are generally to be desired in this step of the 5 process.

In general it may be stated that the separation to be effected in the absorption and stabilizer system is such as to remove from the inlet gas a major portion of the ethane fraction contained 10 therein and substantially all of the fractions heavier than ethane, separation of the thus removed fractions into a lighter normally gaseous hydrocarbon fraction which lends itself most readily to conversion to corresponding unsaturated hydrocarbons without formation of excessive quantities of heavier materials, and a heavier 15 normally gaseous fraction which may be readily polymerized to normally liquid hydrocarbons in a single step. These fractions when later processed as above described will produce a high yield 20 of normally liquid hydrocarbons, the major portion of which will boil in the normal gasoline boiling range.

The pressures applied in absorber 46, separator 25 54, stripper 64 and stabilizer 69 will generally be of the same order as those applied in the initial absorption system as above described.

The pressures maintained in separators 87 and 30 97 will usually range between 100 and 300 pounds per square inch and those in fractionator 90 and separator 109 will usually range from substantially atmospheric to 100 pounds or more.

It will be evident that my process may be directly connected to a natural gas well and the 35 natural gas from the well will be efficiently processed thereby to effect conversion of a major portion thereof to gasoline and a minimum amount of fixed gas which in many cases will be sufficient only to supply the heat requirements of the process. The net result is that the entire production 40 of a natural gas well will be entirely converted to the much more valuable gasoline without the excessive waste of natural gas which now occurs to the great detriment of this important natural 45 resource.

Instead of polymerizing together in coil 83 the 50 unsaturated hydrocarbons formed by the conversion in coil 34 and the heavier normally gaseous hydrocarbons removed from separator 24 through 55 pipe 31, it may be found advisable to separately polymerize each of these materials, although I consider it more advantageous to polymerize the mixture of these materials in the manner described. Similarly other variations may be made 60 in my new process without departing from the spirit and scope of my invention as defined by the appended claims.

I claim:

1. The process for the conversion of normally 65 gaseous hydrocarbons to normally liquid hydrocarbons, which comprises separating said normally gaseous hydrocarbons in an oil absorption step into an initial lighter portion of gases, and a heavier portion of gases, subjecting said heavier 70 portion of gases to a polymerization step, separating unconverted light gases from the effluents of said polymerization step and recovering from said effluents a desirable normally liquid hydrocarbon, recycling a portion of said unconverted light gases 75 through said oil absorption step, condensing a second portion of said unconverted light gases and recycling them through said polymerization step, subjecting said initially lighter portion of gases to a conversion step to effect a partial conversion thereof into unsaturated normally gaseous

hydrocarbons, treating effluents from said conversion step in a second oil absorption step to separate the same into unsaturated hydrocarbons and light gases, recycling said light gases in said conversion step, and adding said unsaturated hydrocarbons to said heavier portion of gases for treatment in said polymerization step. 5

2. A process for the conversion of normally gaseous hydrocarbons to normally liquid hydrocarbons which comprises separating said normally gaseous hydrocarbons into an initial lighter portion of gases, and a heavier portion of gases, subjecting said heavier portion of gases to a polymerization step, separating unconverted gases from the effluents of said polymerization step and recovering from said effluents a desired normally liquid hydrocarbon, recycling a portion of said unconverted gases through said first mentioned separation step, condensing a second portion of said unconverted gases and recycling them through said polymerization step, subjecting said initially lighter portion of gases to a conversion step to effect a partial conversion thereof into unsaturated normally gaseous hydrocarbons, treating the effluents from said conversion step in a separation step to separate the same into unsaturated hydrocarbons and light gases, and adding said unsaturated hydrocarbons to said heavier portion of gases for treatment in said polymerization step. 10 15 20 25

3. A process for the conversion of normally gaseous hydrocarbons to normally liquid hydrocarbons which comprises separating said normally gaseous hydrocarbons into an initial lighter portion of gases, and a heavier portion of gases, subjecting said heavier portion of gases to a polymerization step, separating unconverted gases from the effluents of said polymerization step and recovering from said effluents a desirable normally liquid hydrocarbon, recycling a portion of said unconverted gases through said first mentioned separation step, condensing a second portion of said unconverted gases and recycling them through said polymerization step, subjecting said initially lighter portion of gases to a conversion step to effect a partial conversion thereof into unsaturated normally gaseous hydrocarbons, treating the effluents from said conversion step in a separation step to separate the same into unsaturated hydrocarbons and light gases, recycling said light gases in said conversion step, and adding said unsaturated hydrocarbons to said heavier portion of gases for treatment in said polymerization step. 30 35 40 45 50 55

4. A process for the conversion of normally gaseous hydrocarbons to normally liquid hydrocarbons, which comprises separating said normally gaseous hydrocarbons into a lighter portion and a heavier portion, subjecting said lighter portion to conversion conditions sufficient to convert a part thereof to unsaturated normally gaseous hydrocarbons, separating from the effluent of the said conversion step a fraction containing said unsaturated hydrocarbons and relatively free of methane and hydrogen, and subjecting said fraction together with said heavier portion to polymerization conditions to produce liquid hydrocarbons from the resulting mixture. 60 65 70

5. The process for the conversion of normally gaseous hydrocarbons to normally liquid hydrocarbons which comprises separating said normally gaseous hydrocarbons into a lighter and a heavier portion, subjecting said lighter portion to conversion conditions suitable to effect conversion of a part thereof to unsaturated normal- 75

- ly gaseous hydrocarbons, separating and removing from the products of conversion a fraction containing substantially all of said unsaturated hydrocarbons relatively free of hydrogen and 5 methane, and subjecting unsaturated hydrocarbons together with said heavier portion to polymerization conditions to convert the resulting mixture to normally liquid hydrocarbons.
6. The process for the conversion of normally 10 gaseous hydrocarbons to normally liquid hydrocarbons which comprises separating said normally gaseous hydrocarbons into a lighter and a heavier portion, subjecting said lighter portion to conversion conditions suitable to effect conversion of a part thereof to unsaturated normally 15 gaseous hydrocarbons, independently separating and removing from the products of conversion a fraction containing substantially all of said unsaturated hydrocarbons relatively free of hydrogen and methane, and subjecting unsaturated hydrocarbons together with said heavier portion to polymerization conditions to convert the resulting mixture to normally liquid hydrocarbons.
7. The process for the conversion of normally 20 gaseous hydrocarbons to normally liquid hydrocarbons, which comprises subjecting a mixture of normally gaseous hydrocarbons containing normally liquid hydrocarbons to an oil absorption step conducted under relatively high pressure to separate therefrom a mixture of normally 25 gaseous hydrocarbons and normally liquid hydrocarbons, separating said latter mixture under reduced pressure into a normally liquid fraction, a lighter normally gaseous fraction and a heavier normally gaseous fraction, subjecting said heavier normally gaseous fraction to polymerization conditions under relatively high pressure to convert a portion thereof to normally liquid hydrocarbons, subjecting said lighter normally gaseous 30 fraction to high temperature to effect conversion of at least a portion thereof to unsaturated normally gaseous hydrocarbons, separating and removing from the products of conversion a fraction containing substantially all of said unsaturated hydrocarbons relatively free of hydrogen and 35 methane, and subjecting said unsaturated normally gaseous hydrocarbons to said polymerization conditions concurrently with said heavier normally gaseous fraction.
8. The process for the conversion of normally 40 gaseous hydrocarbons to normally liquid hydrocarbons, which comprises separating said normally gaseous hydrocarbons into a lighter and a heavier portion, subjecting said lighter portion to conversion conditions to effect a partial conversion thereof to unsaturated normally gaseous hydrocarbons, separating and removing from the products of conversion a fraction containing substantially all of said unsaturated hydrocarbons relatively free of hydrogen and methane, subjecting said unsaturated hydrocarbons together with said heavier portion to polymerization con- 45

ditions to convert the resulting mixture to normally liquid hydrocarbons, and separating the effluents of said polymerization into a desirable normally liquid hydrocarbon and unconverted hydrocarbon gases and recycling said gases 5 through said polymerization step.

9. The process for the conversion of normally gaseous hydrocarbons to normally liquid hydrocarbons, which comprises separating said normally gaseous hydrocarbons into a lighter and a heavier portion, subjecting said lighter portion to conversion conditions suitable to effect a partial conversion thereof to unsaturated normally 10 baseous hydrocarbons, separating from said unsaturated normally gaseous hydrocarbons a second portion of lighter gases and subjecting said second portion of lighter gases to said conversion conditions, and subjecting said unsaturated hydrocarbons together with said heavier portion to polymerization conditions to convert the resulting mixture to normally liquid hydrocarbons.

10. The process of converting gas mixtures, containing chiefly C_2 , C_3 and C_4 hydrocarbons, to liquid hydrocarbons which comprises separating the mixture into a fraction containing chiefly 25 heavier components of said mixture and another fraction containing the lighter components, subjecting each fraction in a separate zone to suitable conditions of time, temperature and pressure for converting the gaseous constituents to liquid 30 hydrocarbons boiling within the gasoline boiling range, separating the bulk of the unconverted light gases from the reaction products of the light gas fraction conversion step, charging at least a portion of the products resulting from said conversion of the lighter gases to a common fractionating zone together with reaction products 35 of the heavier gas fraction, separating the incondensable gases from the normally liquid hydrocarbons, and mixing the incondensable gases with the fresh gas prior to separation thereof into fractions.

11. The process of converting gas mixtures, containing chiefly C_2 , C_3 , and C_4 hydrocarbons, to liquid hydrocarbons which comprises separating said mixtures to provide a light gas fraction and a heavy gas fraction, subjecting each fraction in a separate zone to conditions of time, temperature and pressure suitable for converting at least a portion of the gaseous constituents to liquid hydrocarbons boiling within the gasoline range, separating the effluent of the light gas conversion step into a liquid fraction and a vaporous fraction, passing the liquid fraction together with the conversion products of the heavy gas fraction conversion step to a common fractionating zone, separating the incondensable gases from the normally liquid hydrocarbons, and mixing the incondensable gases with the fresh feed gas prior to separation thereof into fractions.

MALCOLM P. YOUNKER.
